TIME-DELAY RELAY

Arthur B. Poole, Harwinton, Conn., assignor to
 Haydon Manufacturing Company, Inc., Tor-
 rington, Conn., a corporation of Connecticut

Application June 4, 1951, Serial No. 229,774

20 Claims. (Cl. 161—1)

1

The present invention relates to electrical relays, and, more particularly, to an improved motor driven time delay relay which is suitable for establishing or interrupting circuit connections to a controlled circuit for a predetermined time interval after energization of the relay.

In relays of the character described, it is customary to use a small, relatively inexpensive, constant speed synchronous motor as a power source for driving the timing mechanism of the relay whereby accurately controlled and long time delays are possible. However, such a motor is of relatively low power output with the result that the contact pressure available to close the relay switch contacts is relatively small. Also, when the driving motor operates the switch contacts directly, the speed of contact closure is dependent upon the motor speed and is necessarily relatively slow in most applications. Certain arrangements heretofore proposed have provided a flexible switch member which is stressed when the relay is energized to store sufficient energy therein to permit rapid and positive closure of the switch contacts at the end of the time delay interval. In general, however, such prior relay structures are not capable of being immediately reset, due to improper meshing of the gears, or the like, are usually quite complicated structurally, and are so designed as to require an inordinate mounting space.

Accordingly, it is an object of the present invention to provide a new and improved time delay relay of the character described.

It is a further object of the present invention to provide a new and improved time delay relay which may be substantially immediately reset to its initial position and wherein a low power driving motor may be employed.

It is another object of the present invention to provide a new and improved time delay relay wherein a low power driving motor may be employed and the time delay interval may be conveniently adjusted by manually operable means.

Still another object of the present invention is to provide a new and improved time delay relay wherein a low power driving motor may be employed and the time required to reset the relay may be conveniently adjusted by manually operable means.

Another object of the present invention resides in the provision of a time delay relay wherein a low power driving motor may be employed and the timing gears remain in mesh throughout the relay cycle to facilitate substantially immediate resetting of the relay.

It is another object of the present invention to 55 invention, the time delay relay includes a con-

2

provide a new and improved low power input time delay relay which is of simple and economical construction, is small in size, and requires only a small amount of space.

5 It is still another object of the present invention to provide an integrating time delay relay which requires a relatively low power driving motor and wherein the relay is substantially immediately reset at the end of a predetermined time delay interval.

A further object of the present invention resides in the provision of a new and improved time delay relay wherein the total time delay may be automatically increased or decreased in 15 accordance with a second signal which occurs after the relay is first operated.

Further objects and advantages of the present invention will become apparent as the following description proceeds and the features of novelty 20 which characterize the invention will be pointed out with particularity in the claims annexed to and forming a part of this specification.

For a better understanding of the present invention, reference may be had to the accompanying drawings in which:

Fig. 1 is a front elevational view of one embodiment of a time delay relay embodying the present invention;

Fig. 2 is a rear elevational view of the relay of Fig. 1;

Fig. 3 is a view taken in the direction of the arrows 3—3 of Fig. 1;

Fig. 4 is a view taken in the direction of the arrows 4—4 of Fig. 1;

Fig. 5 is an enlarged sectional view taken on line 5—5 of Fig. 1;

Fig. 6 is a sectional view taken on line 6—6 of Fig. 5, assuming that Fig. 5 shows the complete structure;

Fig. 7 is a fragmentary view looking in the 40 direction of the arrows 7—7 of Fig. 5, and assuming Fig. 5 shows the complete structure;

Fig. 8 is an enlarged top view of Fig. 1;

Fig. 9 is a front view on a larger scale of the relay of Fig. 1 with portions thereof partially 45 broken away;

Fig. 10 is a somewhat distorted perspective view of the relay of Fig. 1 shown connected in an electrical circuit in order to aid in understanding the operation of the relay in performing certain control functions with respect to a load circuit; and

Figs. 11 and 12 are views similar to Fig. 10 of alternative embodiments of the relay of the present invention.

Briefly, in accordance with one aspect of the

stant speed electric motor which is adapted to drive a differential gear train including a normally stationary differential cage. An electromagnetic relay having an armature normally biased away from the coil thereof is provided and the relay and motor are simultaneously energized at the start of the time delay interval. A switch actuating spring carried by the relay armature is restrained by latch means whereby the armature stresses the spring when the relay is operated. Also, when the relay is operated the driven gear of the differential gear train is held stationary so that the differential cage is rotated in a predetermined path so as to engage the latch means after a predetermined time delay interval to trip the latch means thereby releasing the switch actuating spring and modifying connections to a controlled time delay circuit. Movement of the differential cage beyond the latch trip position causes the motor to be deenergized and when the controlling circuit is opened both the differential cage and latch means are returned to their respective initial positions. In accordance with a further aspect of the invention the time delay interval is conveniently adjusted by adjusting the normal stationary position of the differential cage. Furthermore, the return time of the differential cage may be adjusted to obtain a predetermined reset interval.

Referring now to the drawings, and more particularly to Figs. 1 to 10, inclusive, thereof, the present improved relay is therein illustrated as generally comprising a mounting plate 10 on one side of which is mounted a small self-starting synchronous motor 11 which is adapted to be energized from a suitable single phase source more fully described hereinafter. Also supported from the same side of mounting plate 10 is an electromagnet indicated generally at 12. On the other side of the mounting plate 10 there is provided the time delay mechanism indicated generally at 15 in Fig. 5 of the drawings. The driving motor 11 may be of relatively low power output and includes a standard gear reduction mechanism indicated generally at 13 which reduces the speed of the motor drive shaft and provides a relatively low speed output shaft 14 (Figs. 5 and 10) suitable for driving the timing mechanism 15.

As best shown in Figs. 3 and 7 of the drawings, the electromagnet 12 includes a core structure 18 which is made up of E-shaped laminations on the center leg of which there is positioned the coil 19. An armature 20 is hinged by means of the pin 21 to one leg of the core 18 and is normally biased away from the coil 19 by means of the coil spring 22.

Generally considered, the time delay mechanism 15 includes a triangular shaped back plate 30 which is separated and supported from the mounting plate 10 by means of the spacers 31 and mounting screws 32 respectively. The back plate 30 supports a bearing 34 in which is journaled one end of a timing shaft 35, the other end of which is journaled in the mounting plate 10. The timing shaft 35 carries a driving gear 36 fastened thereto which meshes with a driving pinion 37 rotatable with the motor drive shaft 14. The timing shaft 35 also carries a differential cage 38 rotatable thereon which in turn carries the differential gears 39 and 40 which are fixed except for rotation about their axes relative to cage 38. A driven gear 41 is secured by means of a hub 42 to a ratchet wheel 43, and the driven gear 41 and ratchet wheel 43 are all adapted

to rotate about the timing shaft 35 just as is the cage 38.

As best illustrated in Figures 5, 6, and 9, the differential cage 38 comprises a relatively flat plate 45 which is mounted on the shaft 35 for rotation thereabout and is counter-balanced on one end by means of an arcuate counter weight 46 rigidly attached thereto which offsets the weight of the differential gears 39 and 40 carried by the plate 45. The plate 45 is provided with a recess 47 adapted to receive the differential gears 39 and 40 and these gears are mounted between opposed ear portions 49 and 50 of the mounting plate 45 by means of the pins 51 and 52. The differential gears 39 and 40 mesh with each other as shown at 53 (Fig. 6) while the gear 39 also meshes with the driven gear 41, and the gear 40 meshes with the driving gear 36.

The timing shaft bearing 34 also carries a toothed adjustment wheel 55 which may be rotated by means of an adjustment pinion 56 which meshes with the wheel 55 and may be adjusted by means of an adjustment screw 57 available at the outside of back plate 30. The adjustment wheel 55 is biased against the back plate 30 through the spacer 58 by means of a conical friction spring 60 which is carried on the inner portion of the bushing 34 and effectively presses the adjustment wheel 55 against the back plate 30 so as to maintain this wheel stationary during the time delay operation.

In order to control the initial position of the differential cage 38, the adjustment wheel 55 is provided with a flat side 62 (Fig. 1) to which there is secured a projecting arm 63 which acts as a stop for the differential cage 38. More specifically, the differential cage 38 is provided with a projecting arm 64 which extends beyond the stop arm 63 and the differential cage is normally biased against the stop arm 63 by means of a coil spring 66 which is secured at one end to one of the spacers 31 and extends around and is secured to a grooved bushing 68 which is positioned on the timing shaft 35 and fastened to the cage 38. The spring 66 thus biases the differential cage 38 clockwise as viewed in Fig. 9 so that the arm 64 thereof is normally held against the stop arm 63 as indicated in Fig. 1 of the drawings.

For the purpose of holding the driven gear 41 of the differential gearing stationary so that the differential cage 38 can be rotated during the time delay interval, there is provided a ratchet pawl indicated generally at 70 which is rotatably mounted on the pawl shaft 71 and is provided with teeth 72 adapted to mesh with the teeth on the ratchet wheel 43. The position of the pawl 70 on the shaft 71 is determined by a pawl bushing 69 which is press fitted on the shaft 60 71 and the ratchet pawl 70 is normally held against the bushing 69 and biased into engagement with the ratchet wheel 43 by means of the torsion coil spring 73 (Fig. 7) and is provided at one end thereof with a cam ear 74 which is positioned over an upstanding pin 75 carried by the relay armature 20. As mentioned above, the relay armature 20 is normally biased away from the relay coil 19 by the spring 22 and in this position the pin 75 engages the ear portion 74 and cams the ratchet pawl 70 away from the ratchet wheel 43 as is clearly evident from Fig. 5 of the drawings. Accordingly, when the relay 12 is de-energized as shown in Figs. 3 and 5, and the relay armature 20 is in its uppermost posi-

tion, the ratchet pawl 70 is disengaged from the ratchet wheel 43.

To establish electrical connection to a controlled time delay circuit there is provided a switch mechanism indicated generally at 80 which is mounted on the mounting plate 10 directly above the above-described time delay mechanism as viewed in Figs. 1 and 3 of the drawings. The switch mechanism 80 may comprise a set of normally open or a set of normally closed contacts depending upon the desired control. As illustrated the switch mechanism 80 includes both a set of normally open and a set of normally closed contacts for more universal application and comprises a pair of flexible switch blades 81 and 83 and a central switch blade 82 (Fig. 8) which are embedded in the stacked insulator blocks 84, 85, and 86 and are secured in stacked relation to the mounting plate 10 by any suitable means such as the supporting studs 87 and 88. The flexible switch blade 81 is provided intermediate the length thereof with a switch contact 90 adapted to engage a complementary switch contact 91 positioned on one side of the central switch blade 82. Likewise the flexible switch blade 83 is provided with a switch contact 92 adapted to engage with a complementary switch contact 93 on the other side of the central switch blade 82.

In order to move the flexible switch blades 81 and 83 in unison relative to the central blade 82 so that the switch contacts 90, 91 and 92, 93 may be opened and closed, there is provided a switch actuating member 95 of insulating material which is positioned between the ends of the switch blades 81 and 83 and is provided with a portion 96 of reduced diameter between the blades 81 and 83 (Fig. 7). The notch 96 is adapted to receive the bifurcated end 99 of a switch actuating spring 100, the other end of the spring 100 being secured to the hinged end of the relay armature 20.

For the purpose of restraining the switch actuating spring when the relay armature 20 is closed whereby sufficient energy may be stored in the spring 100 to cause rapid and positive actuation of the contacts 90, 91 and 92, 93 upon the release of the actuating spring 100, there is provided a latch member 105 which is rotatably supported on a latch shaft 106 and is provided with a projecting arm portion 107 which is adapted to fit under the edge of a notch 108 (Figs. 9 and 10) in the side of the switch actuating spring 100. The latch 105 is seated on the upper end of a latch bushing 111 which is press fitted on the shaft 106 and the latch is normally biased into engagement with the spring 100 by means of the torsion spring 109 which also keeps the latch seated on the bushing 111. The latch 105 is adapted to be tripped by the differential cage 38 when the latter member has been rotated counterclockwise, as viewed in Fig. 9 by an amount sufficient to cause the cage 38 to strike the end 110 of the latch 105 and thus rotate the latch clockwise as viewed in Fig. 9 to withdraw the arm portion 107 thereof from beneath the spring 100 and release the spring. The time delay interval is thus equal to the time required for the differential cage 38 to travel from its initial position, as determined by the position of the stop arm 63, to its latch tripping position at which time the switch contacts 92 and 93 are closed and the contacts 90 and 91 are opened.

To provide an indication of the time delay setting of the relay while permitting this time delay setting to be adjusted by means of the adjustment screw 57, there is defined in the

back plate 30 a viewing opening 120 (Fig. 1) through which is visible a circle of graduations 121 inscribed upon the adjustment wheel 55. The graduations 121 are calibrated in terms of the time delay intervals for different positions of the stop arm 63 and a reference marker 122 is provided on the plate 30 to permit an accurate setting of the time delay.

In order to deenergize the driving motor 11 after the switch 80 has been actuated and the desired circuit connections established, there is provided a motor control switch indicated generally at 129 (Figs. 2 and 10) which includes a generally U-shaped flexible switch blade 130 which is normally engaged with a stationary switch contact 131, the switch blade 130 and contact 131 being supported by suitable terminal brackets on a mounting plate 133 which is in turn supported on the plate 10. To open the motor switch contacts after the time delay interval is completed, a tripping arm 135 is provided which is secured to the latch bushing 111 and extends outwardly beyond the switch actuating spring 100 as best illustrated in Figs. 2 and 9, and is adapted to engage an intermediate point on the flexible switch blade 130 when the latch 105 is moved beyond its spring releasing position by the differential cage 38. The operation of the time delay relay discussed above, can best be understood by reference to Fig. 10 of the drawings depicting a somewhat distorted perspective view of the relay of Fig. 1, and, moreover, illustrating this relay in a typical circuit application. The corresponding parts of Fig. 10 have been designated by the same reference numerals as in the preceding figures. Referring to Fig. 10, it may be observed that the incoming line terminals 140 and 141 are connected to energize both motor 11 and the coil 19 of the electromagnet 12 in parallel. The line terminals are also connected to supply a load circuit which should be energized after a predetermined time delay through the normally open switch contacts 92-93 of switch 80. When the synchronous motor 11 is energized, it drives, through the gear reduction mechanism 13 thereof and through the motor drive shaft 14, the motor pinion 37 in a clockwise direction as viewed in Fig. 10, which in turn rotates the driving gear 36 and the timing shaft 35 in a counterclockwise direction. The differential cage 38, which is rotatably supported on the timing shaft 35, is initially held stationary by engagement of the arm 64 thereof with the stop arm 63 on the adjustment wheel 55, the engagement of these members being maintained by the differential cage return spring 66. With the differential cage 38 held stationary, rotation of the driving gear 36 produces rotation of the differential gear 40 in the clockwise direction, which in turn rotates the differential gear 39 in the opposite direction so as to rotate the driven gear 41 and the ratchet wheel 43 in the clockwise direction. However, such operation continues only until the relay armature 20 is in its fully attracted position at which time the ratchet pawl 70 engages the ratchet wheel 43 and stops the driven gear 41 from rotating. When the driven gear 41 is held stationary in the manner described above, the differential cage 38 is then rotated in the counterclockwise direction, the differential gears 39 and 40 being rotated along the peripheries of the rotating driving gear 36 and the stationary driven gear 41 respectively. As a result, the differential cage is moved in the direction shown by the arrow following energization of the elec-

tromagnet 12 and when the armature 20 thereof is in its fully attracted position.

When the electromagnet 12 is operated and the armature 20 thereof moves downwardly under the attraction of the armature coil 19, the switch actuating spring 100, which is secured at one end to the relay armature 20, is restrained by means of the latch 105 which is provided with the extension arm 107 positioned beneath the switch actuating spring 100, the latch 105 being biased into the spring engaging position by means of the spring 109. The outer end of the switch actuating spring 100 engages the switch actuating member 95 of the switch mechanism 80. In the position shown in Fig. 10, the contacts 90 and 91 associated with the switch blades 81 and 82 are closed and the contacts 92 and 93 associated respectively with the switch blades 82 and 83 are opened. Accordingly, in the position shown in Fig. 10 the line circuit is open at the switch 80 and the time delay load circuit 145 is deenergized.

When the differential cage 38 is rotated in the manner described above to a point at which it engages the projecting arm 110 of the latch member 105, this member is rotated so as to remove the arm 107 thereof from beneath the switch actuating spring, thus releasing this spring. When the spring 100 is released, the energy stored by virtue of the stressing action of the armature 20 of the electromagnet 12 produces a snap actuation of the switch mechanism 80 with the result that the contacts 92 and 93 are rapidly and positively closed and the contacts 90 and 91 are rapidly opened. When the contacts 92 and 93 are closed, a connection is made from the line terminal 140 and through the contacts 92 and 93 to the time delay load circuit 145, thus energizing this circuit.

Inasmuch as the motor 11 remains energized after the time delay interval is passed, the differential cage 38 continues to rotate in a counterclockwise direction and continues to rotate the latch 105 in the clockwise direction. As a result, the projecting arm 135 of the latch 105 is moved into engagement with the movable arm 130 of the motor switch 129 so that the motor switch contacts are opened and the motor is deenergized. However, since the line circuit to the terminals 140 and 141 is still maintained, the relay coil 19 remains energized and the timing mechanism remains in the condition described immediately above with power being supplied to the load 145.

When the line circuit is opened, the relay armature coil 19 is deenergized and the armature 20 thereof moves upwardly under the influence of the spring 22 so as to release the ratchet pawl 70 from the ratchet wheel 43. As a result, the differential cage 38 is returned to its initial position by means of the return spring 66 so that the arm 64 thereof is again in engagement with the stop arm 63 carried by the adjustment wheel 55. When the relay armature 20 moves upwardly the switch actuating spring 100 also moves in the same direction so as to permit the arm 107 of the latch member 105 to be moved under the spring 109 by means of the latch return spring 109. When the latch member 105 is moved to the spring engaging position, the arm 135 is disengaged from the motor blade 130 so that the motor is again ready for energization. The time delay relay of the present invention is then ready for another cycle of operation.

In the event that the time delay interval is to be changed, the adjustment screw 57 is rotated

so as to rotate the adjustment wheel 55 thereby varying the stationary position of the differential cage 38. In this connection, it will be understood that the differential cage 38 is moved at a constant rate from its initial position to the latch engaging position under the control of the constant speed motor 11. Accordingly, a variation in the initial position of the cage 38 provides a linear variation of the same delay interval.

From the above description, it will be apparent that there has been provided a time delay relay which has numerous applications such as for turning on the plate circuit of an electron discharge valve a predetermined time after the filament current is turned on.

With the arrangement described thus far, the time delay relay repeats its cycle following each operation thereof. In certain applications it is desirable to have an integrating time delay relay and in Fig. 11 of the drawings there is illustrated such a modification of the present invention. Referring to this figure, the time delay relay shown therein is identical in many respects to the time delay relay of Figs. 1 to 10, inclusive, and the corresponding elements of these relays have been given the same reference numerals. In general, the time delay relay of Fig. 11 embodies the features of the present invention in an integrating type of time delay relay wherein the relay integrates or sums up successive time intervals when a circuit is closed to the line terminals 140 and 141 and energizes the load circuit when the desired total time delay is reached.

More specifically, the ratchet pawl 70 is not controlled by the relay armature 20 as in Fig. 10 but instead is normally biased into engagement with the ratchet wheel 43 by means of the biasing spring 148. Accordingly, when a circuit is closed to the line terminals 140 and 141 and the motor 11 is energized, the ratchet wheel 43 is held stationary and the differential cage 38 immediately begins to move in the counterclockwise direction to engage the latch arm 110. If the circuit to the line terminals 140 and 141 is opened momentarily, the motor 11 and the relay 12 are deenergized and movement of the differential cage is stopped. However, the differential cage is not returned to its starting position upon release of the relay 12 for the reason that the pawl 70 is continuously biased into engagement with the ratchet wheel 43 by the spring 148. The relay thus integrates or sums up the total "on" periods during which a circuit is closed to the line terminals 140 and 141 to obtain the desired total time delay interval. At the end of the total time delay interval the differential cage 38 again trips the latch arm 110 to release the switch actuating spring 100 and close the switch contacts 92 and 93 thereby closing a circuit to the time delay load circuit 145 at the end of the predetermined time delay interval.

When the latch 105 is tripped and the switch actuating spring 100 is moved downwardly, the spring 100 engages the other end of the pawl 70 so as to disengage the pawl 70 from the ratchet wheel 43 and permit the differential cage 38 to be returned to its initial position by means of the spring 66. The pawl 70 is also provided with an upstanding arm 150 which engages the movable contact 130 of the motor switch so that the motor 11 is deenergized at the instant that circuit connections are made to the time delay load circuit 145. When the main circuit is opened the relay coil 19 is deenergized and the switch actuating spring 100 returns to its initial position at which

position it is held by means of the latch 105, the controlled circuit 145 is deenergized, the pawl 70 again engages the ratchet wheel 43, and the motor switch 129 is closed. The integrating relay of Fig. 11 is then set up for another cycle of operation.

There are applications where it is desirable to close a load circuit following a predetermined time delay after actuation of the means for closing the load circuit, but with additional means to vary the time delay should another event or subsequent condition occur during the time delay period. In Fig. 12 of the drawings, there is illustrated a modification of the present invention in which such an arrangement for varying the time delay can be accomplished and the construction is very similar to that of the relay of Figs. 1 to 10 with the provision of means including an additional differential gear mechanism to introduce a change in the speed of operation of the time delay means at variable times after the original time delay has started. The principle involved in the modification of Fig. 12 is that transmission through a differential gear mechanism having a stopped cage is accomplished without change of speed, but if the cage is rotated, it will increase or decrease the velocity of transmission, depending upon the direction of rotation thereof. Referring now to Fig. 12 wherein the corresponding parts are designated by the same reference numerals as in the preceding drawings, the elements are substantially identical with the disclosure of Fig. 10 except for the provision of a second differential gear train generally designated at 149, including a cage 150 very similar to the cage 38 of the differential already described except for the provision of a peripheral gear portion thereon, which gear train is interposed between the motor 11 and the pinion 37. Associated with the differential gear train 149 is a second electromagnet 151 capable of being energized from a suitable signal or power source represented by the terminals 152a and 152b. The electromagnet 151 is adapted to control an armature 153 pivoted as indicated at 154. A spring means 155 normally biases the armature 153 to the position shown in Fig. 12 of the drawings, but upon energization of the electromagnet 151, counterclockwise rotation of the armature 153 about the pivot 154 occurs with the result that a pawl portion 157 of the armature 153 is rendered effective to engage the teeth of the cage 150 and prevent rotation thereof.

For the purpose of increasing or decreasing the speed of rotation of the pinion 37, illustrated as mounted on a shaft 158, above or below the speed at which it would be driven through the differential gear train 149 when the cage of the gear train is held stationary, there is provided a gear train for rotating the cage 150 comprising a gear 161 on the shaft 14 which in turn meshes with a gear 162 mounted upon a suitable shaft 163. For purposes which will become apparent from the following description, the gear 162 is connected to the shaft 163 by a suitable friction clutch schematically designated at 164. The shaft 163 is provided at its other end with a gear 165 drivingly engaged with the gear teeth formed on the periphery of the cage 150. It will be understood that by suitable gearing the cage 150 may be rotated in either a clockwise or counterclockwise direction by the gear 165, but for the illustrated embodiment the cage 150 is rotated in the same direction as the shaft 14. The cage 150 is rotatable about a shaft 167 which corresponds to

the shaft 35 of the other differential gear train already described. Associated with the cage 150 are differential gears 169 and 170. These differential gears are carried by the cage 150 and the differential gear 169 meshes with a driving gear 171 attached to the shaft 167 while the differential gear 170 meshes with a driven gear 172 attached to the shaft 158 to which the pinion 37 is also attached whereby rotation of driven gear 172 will cause similar rotation of the pinion 37. For the purpose of transmitting torque through the differential gear train 149, the shaft 14 is additionally provided with a gear 175 which meshes with the driving gear 171.

15 It will be apparent that when the solenoid 151 is deenergized and the motor 11 is energized that the pinion 37 will be driven through the differential gearing 149 and in addition by virtue of the rotation of the cage 150 the speed of rotation of pinion 37 will be different from what it would be if cage 150 were held stationary. For the arrangement illustrated resulting in rotation of the cage 150 in the same direction as the shafts 14 and 158, the pinion 37 will rotate at a higher speed 20 than if cage 150 were held stationary. Obviously, by an opposite rotation of cage 150, a reduction in the speed of rotation of the pinion 37 relative to its speed when the cage 150 is prevented from rotating is obtained. It will be understood that 25 depending upon the gear ratios employed, the increase or decrease in speed of rotation of the pinion 37 may be controlled as desired. Upon energization of the solenoid 151, however, pawl 157 prevents rotation of the cage 150 which means 30 that shaft 163 must stand still and relative rotation between the gear 162 and the shaft 163 can occur by virtue of the friction clutch 164. Under these conditions, with the cage 150 prevented from rotating pinion 37 is driven through the 35 differential gearing 149 in a readily understood manner without change in speed relative to that of the shaft 14. Consequently, there is provided 40 a relay which provides a time delay in accordance with the formula

$$T = A \pm \frac{t}{k}$$

45 where T is the total time delay, A is the normal or set time delay, t is the time that elapses between the closing of the circuit initiating the normal or set time delay and the occurrence of the second signal energizing or deenergizing solenoid 151, and k is a selected constant. A typical application of the device shown in Fig. 12 is one in which 50 there is a normal time delay for controlling a second circuit such as a circuit connected to the terminals 175a and 175b of the switch 80 after the main circuit to the motor 11 is closed and a second signal which occurs after the main circuit closing, but before the time delay has elapsed 55 modifies the time of controlling the second circuit in dependence upon the amount of time of the normal time delay which has elapsed at the occurrence of the second signal. Under these 60 conditions the device measures the remainder of the original time delay and modifies the subsequent delay by an amount which varies with the remainder of the time delay which it finds. Thus, it actually works a computation based on the time 65 relation of the second signal to the occurrence of the closing of the main circuit.

70 The operation of the device shown in Fig. 12 will readily be understood from the above description. Upon closing the circuit to the line terminals 75 140 and 141, the motor 11 is energized and

drives the differential cage 38 through the differential gearing 149 but modified by virtue of the rotation of cage 150 through shaft 163. After the closure of the main circuit and before the end of the normal or set time delay interval determined by the setting of element 57 and the speed at which pinion 37 is rotated, a second circuit is closed to the terminals 152a and 152b thus energizing the solenoid 151 and stopping the differential cage 150 whereupon the rate of rotation of the differential cage 38 is changed (reduced in the illustrated embodiment) to change the total time delay interval. When the cage 38 trips the latch member 105, a circuit to the load terminals 175a and 175b is modified to establish (in the illustrated embodiment) the circuit connections to the controlled circuit. The motor 11 is again de-energized by further movement of the latch 105 in a manner identical to that described in connection with the relay of Fig. 10 and upon opening of the main line terminals 140 and 141, the switch 80 is restored to its initial position and the relay is reset to its original position.

While the alternative embodiments of the time delay relay of the present invention have been illustrated as provided with a substantially immediate resetting of the differential cage 38 when the line circuit is opened, it will be understood that the differential cage may be returned to its initial position by any suitable control means to obtain a desired resetting interval. For example, a self-starting adjustable return escapement may be driven from the timing shaft 35 in any one of the embodiments of Figs. 10, 11 and 12, so as to control the rate at which the differential cage is returned to its initial position under the action of the return spring 66. The reset interval can be varied in small increments by shifting a counterweight on the end of the escapement. Also, the reset interval may be changed by large increments by varying the gear ratio between the timing shaft 35 and the escapement wheel. In this connection, it will be understood that the reset time will be substantially proportional to the time delay interval due to the fact that the differential cage is moved through a greater distance for a long time delay interval than for a short time delay interval.

It will also be understood that the time delay relay of the present invention may be utilized in a two-period, repeating cycle timer. For example, two time delay relays of the type shown in Figs. 1 to 10, inclusive, of the drawings can be employed to give a timing range for two parts of a given time cycle. Thus, a first time delay relay can be provided with a cycle of twenty-four hours, and a second timer with a cycle of five seconds, to use an extreme example. By connecting the two relays in series, that is, by controlling the second relay from the switch mechanism 80 of the first relay, a time delay control can be obtained once every twenty-four hours within a predetermined five second range. However, in order to provide such an arrangement, it is necessary to provide a starting switch in series with the first driving motor. Such a two-period timing relay may also be made non-repetitive by providing a timed off cycle plus a timed on cycle after which the circuit locks out until a starting switch is actuated to normalize the relays.

Although the invention has been described with the differential cage as the switch actuating element of the differential, it will be understood

that the functions of the three elements of the differential, namely the driving gear, the cage, and the driven gear, may be interchanged. For example, the relay could be designed with the cage as the locked element and the driven gear as the switch actuator. While there have been described what are at present considered to be the preferred embodiments of the invention, it will be understood that various changes and modifications will occur to those skilled in the art and it is aimed in the appended claims to cover all such changes and modifications as fall within the true spirit and scope of the present invention.

15. What is claimed as new and desired to be secured by Letters Patent of the United States is:

1. In a time delay relay, means comprising a switch having relatively movable switch contacts, an electric motor, differential gearing drivingly connected to said motor and including a normally stationary differential cage, an electromagnet having a movable armature, means for simultaneously energizing said electromagnet and said motor, switch actuating energy storage means, means responsive to movement of said armature upon energization of said electromagnet for storing energy in said energy storage means, latch means for maintaining energy stored in said energy storage means, means for holding stationary one of the gears of said differential gearing whereby said differential cage is rotated in a given direction in response to operation of said motor, and means responsive to movement of said cage to a predetermined position for tripping said latch means thereby to release the energy stored in said energy storage means to actuate said switch.
2. In a time delay relay, means comprising a switch having relatively movable switch contacts, 40 an electric motor, differential gearing drivingly connected to said motor and including a normally stationary differential cage, an electromagnet having a movable armature, means for simultaneously energizing said electromagnet and said motor, switch actuating energy storage means, means responsive to movement of said armature upon energization of said electromagnet for storing energy in said energy storage means, latch means for maintaining energy stored in said energy storage means, means responsive to energization of said electromagnet for holding stationary one of the gears of said differential gearing whereby said differential cage is rotated in a given direction in response to operation of said motor, and means responsive to movement of said cage to a predetermined position for tripping said latch means thereby to release the energy stored in said energy storage means to actuate said switch.
3. In a time delay relay, means comprising a switch having relatively movable switch contacts, an electric motor, differential gearing drivingly connected to said motor and including a normally stationary differential cage, an electromagnet having a movable armature, means for simultaneously energizing said electromagnet and said motor, a switch actuating spring, means responsive to movement of said armature upon energization of said electromagnet for stressing said switch actuating spring, latch means for restraining said switch actuating spring in stressed condition, means responsive to energization of said electromagnet for holding stationary one of the gears of said differential gearing whereby said differential cage is rotated in

a given direction in response to operation of said motor, and means responsive to movement of said cage to a predetermined position for tripping said latch means thereby to release said stressed switch actuating means to actuate said switch.

4. In a time delay relay, means comprising a switch having relatively movable switch contacts, an electric motor, differential gearing drivingly connected to said motor and including a normally stationary differential cage, an electromagnet having a movable armature, means for simultaneously energizing said electromagnet and said motor, a switch actuating spring, means responsive to movement of said armature upon energization of said electromagnet for stressing said switch actuating spring, latch means for restraining said switch actuating spring in stressed condition, means responsive to energization of said electromagnet for holding stationary one of the gears of said differential gearing whereby said differential cage is rotated in a given direction in response to operation of said motor, and manually operable means for adjusting the normally stationary position of said cage thereby to vary the time delay control of said relay.

5. In a time delay relay, means comprising a switch having relatively movable switch contacts, an electric motor, differential gearing drivingly connected to said motor and including a normally stationary differential cage, an electromagnet having a movable armature, means for simultaneously energizing said electromagnet and said motor, a switch actuating spring, means responsive to movement of said armature upon energization of said electromagnet for stressing said switch actuating spring, latch means for restraining said switch actuating spring in stressed condition, means responsive to energization of said electromagnet for holding stationary one of the gears of said differential gearing whereby said differential cage is rotated in a given direction in response to operation of said motor, means responsive to movement of said cage to a predetermined position for tripping said latch means thereby to release said stressed switch actuating means to actuate said switch, and means responsive to movement of said cage beyond said predetermined position for deenergizing said motor.

6. In a time delay relay, means comprising a switch having relatively movable switch contacts, an electric motor, differential gearing drivingly connected to said motor and including a normally stationary differential cage, an electromagnet having a movable armature, means for simultaneously energizing said electromagnet and said motor, a switch actuating spring, means responsive to movement of said armature upon energization of said electromagnet for stressing said switch actuating spring, latch means for restraining said switch actuating spring in stressed condition, means responsive to energization of said electromagnet for holding stationary one of the gears of said differential gearing whereby said differential cage is rotated in a given direction in response to operation of said motor, means responsive to movement of said cage to a predetermined position for tripping said latch means thereby to release said stressed switch actuating means to actuate said switch, means responsive to movement of said cage beyond said predetermined position for deenergizing said motor, and means responsive to deenergization of said

electromagnet for returning both said cage and said latch means in their respective initial positions.

7. In a time delay relay, means comprising a switch having relatively movable switch contacts, an electric motor, differential gearing drivingly connected to said motor and including a normally stationary differential cage, an electromagnet having a movable armature, means for simultaneously energizing said electromagnet and said motor, a switch actuating spring, means responsive of movement of said armature upon energization of said electromagnet for stressing said switch actuating spring, latch means for restraining said switch actuating spring in stressed condition, means responsive to energization of said electromagnet for holding stationary one of the gears of said differential gearing whereby said differential cage is rotated in a given direction in response to operation of said motor, means responsive to movement of said cage to a predetermined position for tripping said latch means thereby to release said stressed switch actuating means to actuate said switch, means responsive to movement of said cage beyond said predetermined position for deenergizing said motor, means responsive to deenergization of said electromagnet for returning both said cage and said latch means to their respective initial positions, and escapement means connected to said differential cage for controlling the return time thereof.

8. A time delay relay, comprising a constant speed electric motor, differential gearing driven by said motor and including a differential cage carrying a pair of relatively fixed differential gears, an electromagnet having a movable armature, said armature carrying a switch actuating spring, switch means adapted to be actuated by said spring, latch means for normally holding said spring in stressed position following operation of said electromagnet, means controlled by said armature for restraining the driven gear of said differential gearing whereby said differential cage is rotated in a given direction, and means carried by said differential cage for tripping said latch means after a predetermined rotation of said cage thereby to release said spring and actuate said switch means.

9. A time delay relay comprising a switch having relatively movable switch contacts, a constant speed electric motor differential gearing drivingly connected to said motor and including a normally stationary differential cage carrying a pair of differential gears and a driven gear, an electromagnet having a movable armature, switch actuating energy storage means, means responsive to movement of said armature upon energization of said electromagnet for storing energy in said energy storage means, latch means for maintaining energy stored in said energy storage means, means responsive to energization of said electromagnet for holding stationary said driven gear whereby said differential cage is rotated from an initial position to a tripping position at a speed determined by said constant speed electric motor, and means carried by said cage for tripping said latch means when said cage reaches said tripping position thereby to release the energy stored in said energy storage means to actuate said switch.

10. A time delay relay comprising a switch having relatively movable switch contacts, a constant speed electric motor, differential gearing drivingly connected to said motor and in-

cluding a normally stationary differential cage carrying a pair of differential gears and a driven gear, an electromagnet having a movable armature, a switch actuating spring, means responsive to movement of said armature upon energization of said electromagnet for stressing said spring, latch means for maintaining said spring in a stressed condition, means responsive to energization of said electromagnet for holding stationary said driven gear whereby said differential cage is rotated from an initial position to a tripping position at a speed determined by said constant speed electric motor, means carried by said cage for tripping said latch means when said cage reaches said tripping position thereby to release said spring and permit it to actuate said switch, means controlled by said latch means for deenergizing said motor a predetermined time interval after said cage reaches said tripping position, and spring means for restoring said cage and latch means to their initial positions upon deenergization of said electromagnet.

11. A time delay relay comprising a switch having relatively movable switch contacts, a constant speed electric motor, differential gearing drivingly connected to said motor and including a normally stationary differential cage carrying a pair of differential gears and a driven gear, an electromagnet having a movable armature, a switch actuating spring, means responsive to movement of said armature upon energization of said electromagnet for stressing said spring, latch means for maintaining said spring in a stressed condition, means responsive to energization of said electromagnet for holding stationary said driven gear whereby said differential cage is rotated from an initial position to a tripping position at a speed determined by said constant speed electric motor, means carried by said cage for tripping said latch means when said cage reaches said tripping position thereby to release said spring and permit it to actuate said switch, means controlled by said latch means for deenergizing said motor a predetermined time interval after said cage reaches said tripping position, spring means for restoring said cage and latch means to their initial positions upon deenergization of said electromagnet, and manually operable means for adjusting said initial position of said cage thereby to control the time delay of said relay.

12. A time delay relay comprising a switch having relatively movable switch contacts, a constant speed electric motor, differential gearing drivingly connected to said motor and including a normally stationary differential cage carrying a pair of differential gears and a driven gear, an electromagnet having a movable armature, a switch actuating spring, means responsive to movement of said armature upon energization of said electromagnet for stressing said spring, latch means for maintaining said spring in a stressed condition, means independent of said electromagnet for holding stationary said driven gear whereby said differential cage is rotated from an initial position to a tripping position at a speed determined by said constant speed electric motor immediately upon energization thereof, means carried by said cage for tripping said latch means when said cage reaches said tripping position thereby to release said spring and permit it to actuate said switch, means controlled by said latch means for deenergizing said motor a predetermined time interval after said cage reaches said tripping position, and spring

means for restoring said cage and latch means to their initial positions upon deenergization of said electromagnet.

13. A time delay relay, comprising an electric motor, differential gearing driven by said motor and including a normally stationary differential cage, an electromagnet having a movable armature, means for energizing both said electromagnet and said motor, an electric switch, a switch actuating spring carried by said armature and tending to move therewith, latch means for restraining said spring whereby upon movement of said armature said spring is stressed in response to energization of said electromagnet, means for normally holding stationary one of the gears of said differential gearing independently of the operation of said electromagnet whereby said differential cage is rotated in a given direction during periods when said motor is energized, means responsive to movement of said cage to a predetermined position for tripping said latch means thereby to release said spring and actuate said switch, and means actuated by said spring simultaneously with actuation of said switch for deenergizing said motor and releasing said gear holding means, thereby to permit said cage to return to its initial position.

14. A time delay relay, comprising an electric motor, differential gearing driven by said motor and including a normally stationary differential cage, an electromagnet having a movable armature, means for energizing both said electromagnet and said motor, a switch, a switch actuating spring carried by said armature, latch means for restraining said spring whereby said armature stresses said spring when said electromagnet is operated to move said armature, means for holding stationary one of the gears of said differential gearing whereby said differential cage is rotated in a given direction, means responsive to movement of said cage to a predetermined position for tripping said latch means thereby to release said spring and actuate said switch, and means controllable independently of said electromagnet for changing the rate of rotation of said differential cage following initial movement thereof thereby to change the time delay interval of said relay in dependence upon the operation of said last mentioned means.

15. A time delay relay, comprising an electric motor, differential gearing driven by said motor and including a normally stationary differential cage, an electromagnet having a movable armature, means for energizing both said electromagnet and said motor, a switch, a switch actuating spring carried by said armature, latch means for restraining said spring whereby said armature stresses said spring when said electromagnet is operated to move said armature, means responsive to energization of said electromagnet for holding stationary one of the gears of said differential gearing whereby said differential cage is rotated in a given direction, means responsive to movement of said cage to a predetermined position for tripping said latch means thereby to release said spring and actuate said switch, and means controllable independently of said electromagnet for changing the rate of rotation of said differential cage following initial movement thereof thereby to change the time delay interval of said relay in dependence upon the operation of said last mentioned means.

16. A time delay relay, comprising an electric motor, differential gearing driven by said motor and including a normally stationary differential cage, an electromagnet having a movable armature, means for simultaneously energizing both said electromagnet and said motor, a switch, a switch actuating spring carried by said armature, latch means for restraining said spring to prevent actuation of said switch when said latch means is effective whereby said armature stresses said spring when said electromagnet is operated, means for holding stationary one of the gears of said differential gearing whereby said differential cage is rotated in a given direction, means including a second differential gear train interposed between said motor and said differential gearing and controllable independently of said energizing means for changing the rate of rotation of said cage, and means responsive to movement of said cage to a predetermined position for tripping said latch means thereby to release said spring.

17. A time delay relay, comprising an electric motor, first differential gearing driven by said motor and including a normally stationary first differential cage, an electromagnet having a movable armature, means for energizing both said electromagnet and said motor, a switch, a switch actuating spring carried by said armature, latch means for restraining said spring from actuating said switch whereby said armature stresses said spring when said electromagnet is energized, means for holding stationary one of the gears of said first differential gearing whereby said first differential cage is rotated in a given direction, a second differential gear train including a second differential cage and connected between said driving motor and said first differential gearing, solenoid means adapted to be energized after said electromagnet is operated and independently of said energizing means for controlling the movement of said second differential cage thereby to vary the rate of rotation of said first differential cage, and means responsive to movement of said first differential cage to a predetermined position for tripping said latch means thereby to release said spring and actuate said switch.

18. A time delay relay, comprising an electric motor, first differential gearing driven by said motor and including a normally stationary first differential cage, an electromagnet having a movable armature, means for energizing both said electromagnet and said motor, a switch, a switch actuating spring carried by said armature, latch means for restraining said spring from actuating said switch whereby said armature stresses said spring when said electromagnet is energized, means for holding stationary one of the gears of said first differential gearing whereby said first differential cage is rotated in a given direction, a second differential gear train including a second differential cage and connected between said driving motor and said first differential gearing, a ratchet defined on the periphery of said second cage, solenoid means adapted to be energized after said electromagnet is operated and independently of said energizing means including a pawl for engaging said ratchet for controlling the movement of said 70

second differential cage thereby to vary the rate of rotation of said first differential cage, and means responsive to movement of said first differential cage to a predetermined position for tripping said latch means thereby to release said spring and actuate said switch.

19. A time delay relay, comprising an electric motor, differential gearing driven by said motor and including a normally stationary differential cage, an electromagnet having a movable armature, means for energizing both said electromagnet and said motor, an electric switch, a switch actuating spring carried by said armature and tending to move therewith, latch means for restraining said spring whereby upon movement of said armature said spring is stressed in response to energization of said electromagnet, means for normally holding stationary one of the gears of said differential gearing independently of the operation of said electromagnet whereby said differential cage is rotated in a given direction during periods when said motor is energized, said gear holding means preventing reverse rotation of said cage upon de-energization of said motor providing said cage has failed to move to a predetermined position, means responsive to movement of said cage to said predetermined position for tripping said latch means thereby to release said spring and actuate said switch, and means actuated by said spring simultaneously with actuation of said switch for deenergizing said motor and releasing said gear holding means, thereby to permit said cage to return to its initial position.
20. In a time delay relay means comprising an electric switch, an electric motor, differential gearing drivingly connected to said motor, an electro-magnet having a movable armature, means for energizing said electro-magnet and said motor, switch actuating energy storage means, means responsive to movement of said armature upon energization of said electro-magnet for storing energy in said energy storage means, latch means for maintaining energy stored in said energy storage means, means for holding stationary one of the elements of said differential gearing whereby a second element of said differential gearing is rotated in a given direction in response to operation of said motor, and means responsive to movement of said second element to a predetermined position for tripping said latch means thereby to release the energy stored in said energy storage means to actuate said switch.
